CLAIM

The ornamental design for a releasable small game carrier, as shown and described.

DESCRIPTION

FIG. 1 is an environmental perspective view of a releasable small game carrier showing our new design;

FIG. 2 is a front elevational view thereof;

FIG. 3 is a rear elevational view thereof;

FIG. 4 is a top view thereof;

FIG. 5 is a right side elevational view with the left side being a mirror image thereof; and,

FIG. 6 is a bottom view thereof.

The broken line showing, in FIG. 1 of the person and the rabbit is for illustrative purpose only and forms no part of the claimed design.

FIG. 1**FIG. 4****FIG. 6**FIG. 5

FIG. 3

FIG. 2
